UNITED STATES PATENT OFFICE.

BENJAMIN E. VALENTINE, OF BROOKLYN, NEW YORK, ASSIGNOR TO
CHARLES S. HIGGINS, OF SAME PLACE.

COLD AND FIRE PROOF STORAGE-BUILDING.

SPECIFICATION forming part of Letters Patent No. 298,522, dated May 13, 1884.

Application filed January 16, 1884. (No model.)

To all whom it may concern:

Be it known that I, BENJAMIN E. VALENTINE, of the city of Brooklyn, county of Kings, and State of New York, have invented a new and useful Improvement in Cold and Fire Proof Storage-Buildings; and I do hereby declare that the following specification, taken in connection with the drawings annexed to and forming part of the same, furnishes a full and clear description thereof, sufficient to enable those skilled in the art to which it pertains to make and operate the same.

My invention has for its object the providing of a place of cool storage for those articles whose consistency and preservation are affected by heat, and a place of safe storage for those articles which are of easy combustibility.

It is well known to those familiar with the trades that many articles—such as tallow, oils, fats, &c.—which are preserved with comparative ease in packages at a low temperature will, if stored in the usual manner, or if subjected to changes of temperature by atmospheric heat, undergo changes in their consistency, which cause leakage and often a considerable percentage of waste. Most of such materials are also very combustible, readily ignited, and difficult to save from complete destruction in case of a fire in their place of storage. There are many other articles which, though not susceptible to the changes of consistency, it is equally desirable to protect against dangerous combustion. Heretofore, in case of an accidental ignition of oils and similar products when stored in large quantities in bulk or packages, it has been almost impossible to extinguish them, as, by reason of their lighter gravity, water has but little effect thereon, and many of such substances will readily burn while floating upon the water.

In the drawing the figure represents a cross-section of my improved store-house.

In my method of cold and fire proof storage I select a location which is adjacent to, and preferably entirely surrounded by, water—for example, a small natural or artificial island in a harbor or other body of water. In this location (shown in the drawing at A) I excavate or build, by means of caisson or coffer-dam, a vault whose bottom shall be at all

times below the water-line, and the top of which, C, may be constructed at or any considerable distance below high-water mark. The walls D are of cemented masonry or equivalent water-tight construction, and the vault is 55 preferably divided by longitudinal or cross walls E into bulk-heads or water-tight compartments. The top F, I construct of arched masonry in such a manner as to secure the greatest strength to resist pressure from above 60 or below. Leading from each bulk-head to the adjoining one at or near the floor of the vault, I construct one or more apertures, G, which will allow the flow of water from one compartment to the other. These apertures are opened 65 or closed by gates K, operated in any suitable and well-known manner. At the bottom of the vault a large main or pipe, J, for the admission of water is also constructed, leading from the outer bulk-head to the body of water 70 surrounding the store-house, and is opened and closed by the gate K², operating at the outside wall in a similar manner, to regulate the admission or flow of water. A second main, M, for the admission of water, may be 75 provided at just below high-water mark, or near the top of the vault, which latter main, conducted across the top of the vault, is provided with branches I, leading into each bulk-head, so that the water flowing into this upper 80 main can be diverted at will into any or all of the bulk-heads from above, the admission of the water being controlled by means of gates H in said branches. One or more pumps, P, operated by steam are placed upon the top of 85 the vault, above the water-line, with their suction-pipes R leading to the bottom of the vault. Above the vault a covered store-house of any suitable construction is built, in which are operated the engines, machinery, &c., necessary for pumping, lowering, hoisting, &c. The whole house above the vault may also be used for the storage of articles whose temperature it is not important to keep at a low degree, or which are not especially combustible. 95

It will be seen by the construction which I have described that articles which require to be kept at a low temperature can be deposited directly from ships in the vaults aforesaid; that said vaults being water-tight, but 100

situated below the level of the surrounding water, will be kept at a temperature which will seldom equal and need never exceed that of the surrounding water; that in case of fire, or in case it is desired for any other reason to introduce water into the vaults, the same can be introduced from above from the main M or from below by the main J, or any compartment can be flooded by the branches I.

10 In case it is necessary to flood the vaults or bulk-heads wherein oils or other materials of a lighter gravity than water are stored, iron bands or rods N may be constructed on the inner side of the arched vaults, which shall protect the masonry from the upward pressure of the packages, which would otherwise float, and retain them submerged without injury to the masonry.

Having thus described my improved method 20 of storage, what I claim as my invention, and desire to secure by Letters Patent, is—

1. A warehouse consisting of a vault or vaults built below the water-level and surrounded by a natural or artificial embankment 25 of earth, as shown at A, around which is the sea or other natural body of water, said vaults being normally free from water, but provided with means, substantially as described, for flooding them.

2. A warehouse having vaults built below the water-level, provided with means for being flooded and emptied, as desired, and surrounded by a natural or artificial embankment of earth, as shown at A, and outside of the embankment by the sea or other natural body 35 of water, and having a superstructure erected over said warehouse-vaults, said superstructure serving the purpose of an ordinary warehouse.

3. A vault for cold and fire proof storage 40 consisting of a wholly or partially submerged vault divided into compartments, substantially as described, and provided with mains M and J, for the access of water, and gates H K, for regulating the supply thereof, substantially as and for the purposes described.

4. The cold and fire proof vault, constructed substantially as described—to wit, in submerged compartments provided with one or more mains, and branches for admitting the 50 flow of water, the pump P, and the gates H K, substantially as and for the purposes described.

BENJ. E. VALENTINE.
